UNITED STATES PATENT OFFICE.

ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FEELER MECHANISM FOR LOOMS.

1,387,325.

Specification of Letters Patent.

Patented Aug. 9, 1921.

Application filed March 8, 1920. Serial No. 364,159.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms through the agency of which filling is replenished from time to time.

In order that perfect cloth may be woven on a feeler loom, it is essential that the shuttle shall lay a full pick of filling on each picking movement, and that prior to the complete exhaustion of the filling in the shuttle, replenishment of the filling supply shall be effected. On the other hand, the amount of filling that remains upon the filling carrier or bobbin when replenishment is effected, constitutes waste. It is therefore the aim of a feeler mechanism to minimize this waste as far as possible without at the same time laying a partial or imperfect pick of filling.

In order that the feeler mechanism may perform the desired functions, it is essential that it be sensitive and responsive both to the presence and substantial absence of filling in the shuttle, and that upon detection of substantial exhaustion, but prior to complete exhaustion, it shall set a train of mechanism to effect replenishment of filling. One of the types of feeler mechanisms heretofore devised has provided for the "side swipe" movement of a feeler or movement of the feeler in a direction longitudinally of the shuttle when the filling became substantially exhausted, and advantage has been taken of this side swipe movement of the feeler to effect replenishment of filling. The present invention relates to this general type of feeler mechanism, and an important feature thereof consists in a feeler and a feeler actuator both of which enter the shuttle on a detecting beat and engage a surface within the shuttle, and means connecting the actuator and feeler which, under the frontward pressure against the actuator, tends to move the feeler longitudinally of the shuttle or impart the side swipe movement thereto. In carrying this feature of the invention into prac-

tical effect, the feeler preferably projects to a small extent rearwardly of the end of the actuator, so that it will first engage the surface within the shuttle on a detecting beat, and if a working supply of filling is present, 60 the roughened or toothed end of the feeler will sink into the mass of filling and prevent its lateral or side swipe movement under the frontward push against the actuator transmitted through the train of mechanism connecting the actuator and feeler.

Another important feature of the invention consists in the feeler carrier on which both the feeler member and actuator are mounted, and a train of mechanism including a rack and pinion between the feeler and actuator, tending to impart lateral or side swipe movement to the feeler by frontward pressure upon the actuator on a detecting beat.

The above features and other novel elements and combinations of parts will hereinafter be described in connection with the accompanying drawings which illustrate one good, practical form of the invention.

In the drawings:—

Figure 1 is a perspective view of the feeler side of a loom, some of the parts being omitted for clearness of illustration, and others broken away;

Fig 2 is a plan view on an enlarged scale, some of the parts being shown in section, illustrating the action of the feeler mechanism when, on a detecting beat, a working supply of filling is present in the shuttle;

Fig. 3 is a view similar to that of Fig. 2, showing the action of the feeler mechanism when the supply of filling in the shuttle has become substantially exhausted.

The loom frame 1 may be of usual construction, and has secured thereto the bearings 2, one at each side of the loom frame in which is mounted the transverse or rock shaft 3, normally held in a predetermined 100 rotative position by a spring, as usual in this class of looms, and adapted for rocking movement to effect replenishment of filling. The rock shaft 3 and its connection with the filling replenishing mechanism are or may be 105 of usual construction, and being well understood by those skilled in the art, its description here is unnecessary, as the details thereof form no special part of the present invention.

Secured to and rising from the transverse or rock shaft 3, is the arm 4, to which is pivoted at 5 the latch 6, the rear end portion 7 of which is adapted at times to be engaged by an operating member 8 which may be connected to a going part of the loom, as for instance, the cam follower.

The lay 9 has the usual shuttle-box 10, the front wall of which is slotted at 11 to register with a corresponding slot 12 in the adjacent wall of the shuttle 13 when the latter is in the detecting box, as indicated in Fig. 1. The shuttle 13 has mounted therein the filling carrier or bobbin 14, on which is wound the filling 15. These parts may be of usual and well known construction. The present invention contemplates that the feeler and the actuator shall be supported upon a feeler carrier movable toward and from the front of the loom, and normally held in its rearward position. There are several forms of such carriers well known in the art, but in the present instance of the invention, the carrier, as will hereinafter appear, is formed as a reciprocating slide, although any appropriate form of carrier might be employed.

The shipper stand 16 has extending therefrom the slotted bracket 17 to which is adjustably secured the bracket 18 constituting an appropriate support for a feeler stand 19, which may be adjustably secured thereto by means of the bolts 20 and the slot 21 formed in the feeler stand.

Mounted on the feeler stand 19 is the feeler carrier 22 having a forwardly extending stem 23 which passes through an opening in an upstanding bearing 24 at the front of the feeler stand. The rear portion 40 of the feeler carrier is guided for reciprocating movements in an appropriate bearing formed in the rear upstanding flange 25 of the feeler stand. A spring 26 surrounds the stem 23 of the feeler carrier, in the present instance, and normally tends to hold the feeler carrier in its back or rearward position as indicated in Fig. 1, and a stop, such as the pin 27, limits the rearward movement of the feeler carrier.

The feeler carrier 22 may be appropriately constructed to support the feeler and feeler actuator, but in the present instance of the invention the feeler carrier is formed of the bottom plate 28 and an overlying or top plate, as indicated in Fig. 1, the two plates being appropriately secured together by proper securing means such as the rivets or like devices 29, the construction being such that the feeler carrier presents a housing or inclosing structure in which the feeler and feeler actuator are mounted.

Mounted on the feeler carrier for lateral or side swipe movement is the slide 30, best shown in Figs. 2 and 3. The slide 30 may be appropriately guided in its lateral move-

ments and also be limited in the amplitude thereof. In the present instance the slide 30 is provided with a slot 31, through which extend the guide and limiting pins 32 and 33, whereby the slide 30 will be guided in its lateral or transverse movements, and the amplitude of said movements be restricted. The slide 30, in the present instance, is formed as a rack having the teeth 34 which are engaged by the teeth of the pinion 35 mounted for rotative movement at 36 on the feeler carrier and operatively engaged with the feeler actuator. The feeler actuator 37 is guided for forward movement relative to the feeler carrier 22 and is guided in such movement by the pins 29 and 32, as indicated in Figs. 2 and 3. The actuator 37 has a series of teeth 38 which engage the pinion 35, the construction being such that should the actuator 37 be moved toward or from the front of the loom relative to the feeler carrier, it will impart rotative movement to the pinion 35 and lateral or transverse movements to the rack or slide 30.

The rack or slide 30 has connected thereto the feeler 39, the rear end portion of which is provided with the teeth 40. In the present instance the rack or slide 30 has a sleeve 41 through which loosely passes the feeler 39, and a spring normally acts upon the feeler member to hold its rear toothed end portion 40 extended rearwardly a short distance beyond the end 42 of the feeler actuator. The spring for effecting the yielding positioning movement of the feeler, as described, may be variously contrived, but in the present instance it consists of a spring wire 43 wound about the stud 44 mounted on the feeler carrier. One end of the spring at 45 is secured to the rack or slide 30, and the other end of the spring at 46 extends into an aperture formed in the feeler 39, the construction being such that the spring normally acts to maintain the feeler member in its rearward feeling position.

As hereinbefore stated, the roughened or toothed end 40 of the feeler extends rearwardly a short distance beyond the rear end 42 of the feeler actuator; and when a working supply of filling is present in the shuttle on a detecting beat, the toothed or roughened end portion 40 of the feeler will engage the filling mass and sink into it, as the lay moves forward on a detecting beat, and thereafter the end 42 of the feeler actuator will meet the filling mass and by forward push against it, will tend to actuate the train of mechanism connecting the feeler actuator and feeler to move the feeler member laterally, or in a direction longitudinally of the shuttle. The teeth or roughened portion 40 of the feeler, however, having sunk into the mass of filling, will resist such lateral movement and the forward push against the feeler actuator will move the feeler carrier

and its associated parts frontwardly without accomplishing lateral movement of the feeler. When, however, the filling is substantially exhausted on a detecting beat, the 5 feeler will again engage the surface within the shuttle, and inasmuch as the filling is substantially exhausted, it will not resist lateral movement of the feeler under the frontward push against the feeler actuator 10 transmitted through the train of mechanism connecting the feeler actuator and feeler, so that the feeler will partake of its movement laterally, or in a direction longitudinally of the shuttle.

15 Advantage is taken of the lateral movement of the feeler under the conditions stated, to effect replenishment of filling; and one convenient means to this end is best shown by Fig. 1, wherein the slide or rack 20 30 is shown as connected to a transmitter 47, the other end of which is connected at 48 to a bell crank lever 49 pivoted at 50 to a stand 51 rising from the loom frame. One member 52 of the bell crank lever underlies the 25 latch 6 and a stop 53 limits movement of the bell crank in one direction, the construction being such that should the feeler and the slide or rack 30 which carries it, be moved laterally on a detecting beat, in 30 the manner hereinbefore described, the end 7 of the latch 6 will be placed in the path of the operating member 8, frontward movement of which will effect rocking movement of the transverse or rock shaft 3, to effect 35 replenishment of filling in the usual manner.

It is of importance that the feeler shall not partake of its lateral movement or movement longitudinally of the shuttle on a detecting beat, provided the filling in the shuttle 40 has not reached the desired degree of exhaustion, and to insure against such movement when a sufficient supply of filling is still present in the shuttle, the spring 43 is placed under increasing tension as the rack 45 or slide 30 moves laterally under the frontward push against the actuator 37, to thereby more forcefully push the feeler rearwardly to cause its toothed or roughened end 40 to press with increasing force against the 50 surface within the shuttle. If such surface should still be constituted by sufficient filling to continue weaving, the effect will be to prevent sufficient lateral movement of the feeler and slide to effect replenishment of filling 55 until the working supply in the shuttle reaches the desired degree of exhaustion.

What is claimed is:—

1. A feeler mechanism, comprising, in combination, a feeler and a feeler actuator 60 both of which engage a surface within the shuttle on a detecting beat, a laterally movable slide carrying the feeler, means connecting the feeler actuator and slide tending to cause lateral movement of the slide by the 65 frontward push upon the actuator and held

from effecting such movement by engagement of the feeler with the filling on a detecting beat until the filling is substantially exhausted, and means for effecting replenishment of filling when the slide is moved laterally on a detecting beat. 70

2. A feeler mechanism, comprising, in combination, a feeler and a feeler actuator both of which engage a surface within the shuttle on a detecting beat, a laterally movable slide carrying the feeler, a spring normally projecting the feeler rearwardly on the slide and yielding frontwardly on a detecting beat to permit the actuator to engage the surface within the shuttle, means connecting the feeler actuator and slide tending to cause lateral movement of the slide by the frontward push upon the actuator and held from effecting such movement by engagement of the feeler with the filling on a 80 detecting beat until the filling is substantially exhausted, and means for effecting replenishment of filling when the slide is moved laterally on a detecting beat. 85

3. In a feeler mechanism for looms, the combination of a feeler, a feeler actuator both of which engage a surface within the shuttle on a detecting beat, a laterally movable rack carrying the feeler, a pinion engaging the rack and adapted to be rotated by frontward movement of the actuator relative to the feeler and held from such rotation by engagement of the feeler with the filling on a detecting beat until substantial exhaustion of filling, and mechanism positioned by lateral movement of the feeler for effecting replenishment of filling. 90

4. In a feeler mechanism, the combination of a feeler carrier mounted for movement toward and from the front of the loom, a feeler and a feeler actuator both movably mounted on the feeler carrier to engage a surface within the shuttle on a detecting beat, a laterally movable slide mounted on the feeler carrier and connected to the feeler, and means operated by frontward movement of the actuator relative to the feeler tending to move the said movable slide laterally on a detecting beat and held from effecting such movement by engagement of the feeler with the filling until substantial exhaustion thereof. 105

5. In a feeler mechanism for looms, the combination of a feeler carrier mounted for movement toward and from the front of the loom, a feeler and a feeler actuator mounted on the feeler carrier, a rack and pinion connection between the feeler and feeler actuator for causing the frontward pressure on the actuator to impart lateral movement to the feeler, which movement is prevented by engagement of the feeler with the filling on a detecting beat until substantial exhaustion of filling, and means for effecting replenishment of filling when the feeler is given its lateral movement. 120

6. In a feeler mechanism for looms, the combination of a feeler carrier mounted for movement toward and from the front of the loom, a feeler and a feeler actuator mounted 5 on the feeler carrier and extending rearwardly to engage a surface within the shuttle on a detecting beat, a rack and pinion connection between the feeler and feeler actuator for causing the frontward pressure 10 on the actuator to impart lateral movement to the feeler which movement is prevented by engagement of the feeler with the filling on a detecting beat until substantial exhaustion of filling, and means for effecting replenishment of filling when the feeler is given its lateral movement.
7. In a feeler mechanism for looms, the combination of a feeler and a feeler actuator mounted for relative movement toward 20 and from the front of the loom, a slide for supporting the feeler and movable bodily therewith in a direction longitudinally of the shuttle, connections between said slide and actuator including a rotary element 25 tending to impart movement to the feeler longitudinally of the shuttle by relative frontward movement of the actuator and held from effecting such movement by engagement of the feeler with the filling until 30 substantial exhaustion thereof, and means to cause replenishment of filling when the feeler is moved longitudinally of the shuttle on a detecting beat.
8. A feeler mechanism, comprising a 35 feeler, a laterally movable slide carrying the feeler, a feeler actuator, a train of mechanism tending to move the slide laterally by the frontward push upon the actuator and held from effecting such movement by engagement of the feeler with the filling on a 40 detecting beat until substantial exhaustion of filling, and a spring rendered effective to increase the push of the feeler against the surface within the shuttle by lateral movement of the slide.

9. In a feeler mechanism for looms, the combination of a feeler carrier mounted for movement toward and from the front of the loom, a feeler and a feeler actuator, both of which are supported by the feeler carrier, and rack and pinion connections between the feeler and feeler actuator which transmit the frontward pressure upon the feeler actuator on a detecting beat into a side pressure upon the feeler and effect movement of the feeler longitudinally of the shuttle when the filling is substantially exhausted and the feeler is freed to such movement.

10. In a feeler mechanism for looms, the combination of a feeler carrier mounted for movement toward and from the front of the loom, a feeler and a feeler actuator mounted upon the feeler carrier, rack and pinion connections between the feeler and feeler actuator constructed and arranged 60 to transmit relative frontward movement of the actuator into movement of the feeler in a direction longitudinally of the shuttle, and means set in operation by such movement of the feeler when filling is substantially exhausted to effect replenishment of filling.

11. In a feeler mechanism for looms, a feeler carrier mounted for movement toward and from the front of the loom, a feeler that is mounted upon the feeler carrier, a feeler actuator that is also mounted upon the feeler carrier independent of the feeler and for frontward movement on the carrier relative to the feeler, and a train of mechanism including a rack and pinion 75 mounted on the feeler carrier and connecting the feeler and feeler actuator for converting frontward movement of the actuator relative to the feeler into side movement of the feeler when filling is substantially exhausted.

In testimony whereof I have signed my name to this specification.

ISAAC SNOW.
